SAFETY LATCH FOR HOOKS

Dario Buccicone and Charles M. Shank,
Gary, Ind.

Application November 9, 1936, Serial No. 109,974

4 Claims. (Cl. 294—83)

This invention has reference to safety latches for hooks and has, as one of its objects, the provision of a safety latch that retains a position which either bridges or exposes the open portion of the hook, depending upon the initial position given the latch.

The above and further objects will be apparent from the following description and by reference to the accompanying drawing in 10 which:

Figure 1 is an elevation of one embodiment of our improved safety latch for hooks;

Figure 2 is a side elevation of Figure 1;

Figure 3 is an elevation of the embodiment of 15 our invention, shown in Figure 1, with the safety latch in a non-latching position; and

Figure 4 is a side elevation of Figure 3.

Referring to the accompanying drawing, the numeral 4 indicates, as a whole, a standard hook, as for example, of the forged type used on a 20 crane. Removably closing the mouth of the hook 4 is a latch 6 which more particularly includes arms 10 that are provided with inwardly extending end portions 8. The arms 10 extend 25 in sliding relation with the hook 4 on both sides thereof. Welded or otherwise secured to, or formed integral with, the hook 4 are guides 12 which receive and support the arms 10 for sliding movement to and from latching position, as shown in Figures 1 and 3 of the drawing.

To further support the latch 6 during its sliding movement and to assist in locking it in latching or non-latching position, links 14 are pivotally secured, as by a bolt 16, to the arms 10. 35 The other ends of the links 14 are pivotally secured to a boss 18, either secured to or formed integral with the hook 4.

As will be seen from the drawing, the pivotal connection between the links 14 and boss 18 is 40 vertically below and at about the mid-point of the travel of the bolt 16 from latching to non-latching position so that in either position of the latch 6 the links 14 make substantially equal angles with the vertical. This effects a gravity hold for the latch 6 in either position and, moreover, in the latching position of the links 14 the guides 12 prevent the latch from being knocked away from the mouth of the hook 4.

In order to provide means for readily moving 50 the latch 6, a centrally positioned and backwardly extending handle 20 is provided therefor. The forward or latching movement of the latch 6 is limited by the engagement of the end portions 8 with the back of the hook 4. The 55 arms 10 are of such length, as shown in the

drawing, that they extend substantially into engagement with the point of the hook 4 when the latch 6 is in its forward position. Stud pins 22, secured to the outside of the ends of the arms 10, engage with the guides 12 to limit the movement of the latch to a non-latching position. Thus, in non-latching position, the latch 6 is completely clear of the mouth and inner periphery of the hook, as shown in Figure 3, and does not interfere with the placing of chains or 10 cables on the hook 4.

While we have illustrated and described one specific form of our invention, it will be appreciated that various modifications thereof can be made without deviating from the scope of our 15 invention as defined by the following claims.

We claim:

1. Apparatus of the class described comprising, in combination, a hook, a latch for closing the mouth of said hook, and means mounting 20 said latch on said hook for movement from a latching to a non-latching position, said means being adapted to hold said latch in both latching and non-latching positions due to the force of gravity on said means.

2. Apparatus of the class described comprising, in combination, a hook, a latch for closing the mouth of said hook, guide means carried by 25 said hook for positioning said latch, means limiting the movement of said latch and means associated with said latch for moving it from a latching to a non-latching position, said last named means being so constructed and arranged whereby the weight thereof holds said latch against undesired movement when said latch is 30 in either the latching or non-latching position.

3. Apparatus of the class described comprising, in combination, a crane hook, a latch for closing the mouth of said hook, guides slidably 35 positioning said latch on said hook, means associated with said latch for limiting its movement from its initial latching to its initial non-latching positions, links, means pivotally securing said links to said latch, means pivotally securing said links to said hook at a point vertically below substantially the mid-point of the arc traversed by said first named means when said latch is moved from a latching to a non-latching position.

4. Apparatus of the class described comprising, in combination, a crane hook, a latch provided with spaced parallel arms for closing the mouth of said hook, guides slidably positioning 50 said latch on said hook, links, means pivotally securing said links to said latch, means piv- 55

totally securing said links to said hook at a point vertically below substantially the mid-point of the arc traversed by said first named means when said latch is moved from a latching to a non-latching position, means limiting the movement of said latch to the initial latching position thereof and means limiting the movement

of said latch to the initial non-latching position thereof, said latch being so constructed and arranged that the force of gravity holds it in both its latching and non-latching positions.

DARIO BUCCICONE.
CHARLES M. SHANK.
